FURNACE PORT

Samuel A. Forter, Bellevue, Pa., assignor to Forter-Teichmann Company, a corporation of Pennsylvania

Application December 5, 1936, Serial No. 114,405

6 Claims. (Cl. 263—15)

My invention relates to regenerative furnaces, and more particularly to the ports of such furnaces. In exemplary way the invention will be described as it has been applied to glass furnaces.

5 The usual glass furnace includes one or more pairs of cooperating ports that communicate with regenerators arranged in known way at opposite sides of the furnace. Air for sustaining combustion within the furnace is heated by the checker-work in one regenerator while the hot waste gases of the furnace are led through and heat the checkerwork in the other regenerator. The heated air, together with liquid or gaseous fuel, is introduced to the furnace chamber through the 10 port or ports at one side of the furnace, and the waste gases find escape through the port or ports at the opposite side. And from time to time the furnace is reversed, and the ports which had been serving as the firing ports become the 15 outgo ports, and the ports which had been serving as the outgo ports become the firing ports. The art is familiar with such practice and further detail is needless.

20 Ports in large number and of various designs have been proposed and tried in practice, and it has been found that ports which operate with high efficiency as firing ports fail to function with desired efficiency as outgo ports. Alternately, ports which are particularly effective as 25 outgo ports fail to give highest efficiency as firing ports.

My object is to provide a port in which high efficiency is obtained both when the port serves as a firing port and when it serves as an outgo port. The invention consists in refinements in port construction and in method of operating a port to fire a furnace. My port is of simple and economical construction, and is easily inspected and maintained in service. The port is of such 35 design that so far as may be the gases flowing therethrough flow in stream-lines. When serving as a firing port, the walls of my structure are by a blanket of air protected from the burning fuel, and, when serving as an outgo port, maximum capacity for the conduction of waste gases is provided. Additionally, the port of my design minimizes and eliminates the usual tendency for dust and molten particles entrained in the waste gases streaming from the furnace, to settle 40 and collect in the port and thereby interfere with normal operation.

In the accompanying sheet of drawings, Fig. I is a view in axial and vertical section of a port embodying the invention, and Fig. II is a view

of the port in cross section, on the plane II—II of Fig. I.

In the drawing, the reference numeral 1 indicates the roof, and 2 the side-wall of a fragmentarily illustrated glass furnace or tank F. 5 The numeral 3 is applied to one of the regenerators which in known way is organized with the furnace F, and a port P, illustrative of the invention, establishes communication immediately from the top of the regenerator to the chamber 10 of the furnace. In well-known manner, the furnace, the regenerator, and the port are constructed of refractory bricks and tiles, laid up with mortar and reinforced and tied with structural steel and tie-rods. 15

The port P includes a horizontally extending throat or passageway 10 that opens at its right-hand end (Fig. I) into the furnace chamber, and at its left-hand end opens into a passage 11 extending upward from the top 5 of the 20 checkerwork embodies, as usual, in regenerator 3. Only the upper portion of the regenerator 3 and the top course of checker-blocks of the checker-work 5 are shown in the drawing. The floor of the port P is constructed of refractory slabs 25 12 that are readily replaceable in service, and the roof of the port and upper end of passage 11 are covered in common by a horizontally extending arch 13. And it is to be noted that the side-walls 9, 9 of the port (and the roof and floor 30 13, 12, respectively) extend in parallelism, whereby the throat 10 of the port is of substantially uniform cross-sectional area throughout its horizontal extent.

When the port is operating as a firing port, 35 air flows upward through the hot checkerwork in the regenerator 3 and is heated. Under the influences of buoyancy, and of draft produced by the usual furnace stack (not shown), the heated air sweeps into the horizontal throat 10 of the 40 port. Fuel is introduced to the streaming air, and a mixed and burning column of fuel and air is projected from the throat 10 into the furnace F.

In accordance with my invention, the preheated 45 air rising from the hot checkerwork 5 is caused to flow in divided stream into the throat of the port, and to such end I provide in the port a vertical partition 14, whose upper edge 14a lies slightly above the level of the floor (12) of the 50 port. The partition 14 extends transversely between the side walls 9, 9 of the port and parallels the side-wall 2 of the furnace. Thus, the uptake 11 is divided into two passages 11a and 11b; the stream of air flowing upward in passage 11b 55

is greater than the stream in the passage 11a, and the larger of such vertical streams is more remote from the furnace F than the smaller. Into the smaller and less remote stream of air 5 sweeping upward through passage 11a, I introduce fluid fuel. The fuel is natural gas in this case.

More particularly, a fuel injector or burner is arranged in the vertical wall of the port nearest 10 to the furnace, and such injector comprises a rectangular manifold 4 installed in the vertical end-wall 8 of the port. The manifold 4 is constructed of refractory material. Through the rear-wall of the manifold a fuel-introducing pipe 15 6 extends, and in the front-wall an elongate, narrow, horizontal slot 7 opens. Advantageously, the heat-resisting manifold 4 is embodied as a unit of masonry in the vertical end-wall 8 of the port, and it will be perceived in Fig. II that 20 the burner manifold is centered in the vertical mid-plane of the port, with the opposite ends of the slot 7 spaced from the respective side-walls 9, 9 of the port. The feed pipe 6 introduces the 25 gaseous fuel into a chamber c within the burner manifold, and the fuel streams from such chamber (through slot 7) in the form of a thin sheet of gas.

It will be observed that the fuel enters the 30 burner manifold at a point adjacent to the floor chamber c, and leaves by way of slot 7 located adjacent to the top of such chamber. Upon entering the chamber c the gas expands and its 35 velocity falls; then, as it flows through slot 7, its velocity rises again. In service my fuel-injecting manifold or burner has proved very efficient. Turbulence of flow in the injected fuel 40 is minimized—the flow of fuel is stream-line as it is directed angularly into the ascending stream of preheated air in passage 11a. Upon the merging of the fuel with the heated air in passage 11a, combustion begins, and it will be understood 45 that the passage 11a comprises a primary combustion chamber, while the hot air rising therein comprises the primary combustion air. In the 50 drawing, I have employed short, dark arrows to indicate the flow of the fuel introduced to the port, and relatively long arrows to indicate the movement of the preheated air.

As may be visualized in Fig. I, the sheet of gaseous fuel injected into the passage 11a is deflected upward and merges tangentially with the 55 vertical stream of primary combustion air flowing upward in passage 11a. Between the opposite ends of slot 7 and the respective side-walls 50 of the port, vertically flowing side-currents of air operate to screen the side-walls of the port and to prevent undue lateral spreading of the injected sheet of fuel. (Note the arrows in Fig. II, the 60 short arrows indicating the fuel and the long arrows the air.)

As has been already mentioned, the air flowing in passage 11a comprises the smaller component of the double or divided stream flowing upward from the checkerwork 5. The larger 65 component of the divided stream, rising through passage 11b, flows horizontally over the top of partition 14, across the top of passage 11a, and into the throat 10 of the port, with the consequence and effect that the merged and partially 70 mixed streams of fuel and air flowing vertically upward to the top of passage 11a are (by the horizontal stream of air) gradually bent or folded into a horizontal course of flow, as the arrows indicate in Fig. I. The air entering the throat 75 10 from passage 11b forms a horizontal curtain

of air over the mixed stream of fuel and air rising from passage 11a and flowing over the floor 12 of the port, and this enveloping curtain of air, and the side-currents of air mentioned above, protect the roof and side-walls of the port from immediate contact with the burning gases. As the movement of the column of fuel and air progresses from left to right (Fig. I) in the throat 5 10 10, combustion-sustaining air is by the burning gases drawn from said enveloping curtain of air. Thus, the air flowing from the passage 11b and forming the air curtain in the throat 10 provides secondary combustion air, and the throat 10 itself may be considered a secondary combustion 15 chamber.

Contrary to usual practice, the mouth M of the port is not constricted, but is of the same cross-sectional area as the throat 10. The velocity of flow of the burning column of fuel and air projected into the furnace F is produced solely 20 by the buoyancy of the heated air rising into the port and the draft of the furnace, augmented by the effect of the expansion of the gases, as combustion progresses from the point of fuel admission (slot 7) to the mouth M of the port. 25 As already mentioned, the opposite walls of the port are parallel throughout; the cross section of the column of fuel and air within the throat 10 is held to uniform value—there is no choking of flow within the port, and turbulence is 30 reduced to a minimum.

If desired, auxiliary streams of fuel may, by means of orifices 16, be projected through the opposite side-walls of the port and into the burning 35 column streaming through the throat 10.

From the foregoing description, it will be understood that, in the operation of the port P, preheated air is led upward in divided stream from the hot checkerwork of the regenerator 3; that one of the components of such divided 40 stream is larger than the other, and more remote from the furnace F into which the port opens; that a sheet of fluid fuel is directed into the smaller component of the vertically streaming air and caused to merge tangentially therewith; that the merged streams of fuel and air about to enter the throat 10 are deflected from a vertical into a horizontal line of flow; that the air of the larger component of the vertically divided 45 stream is caused to form a curtain over the deflected and horizontally flowing stream of fuel and air; and that the cross-section of the gaseous column in throat 10 is held to substantially uniform value, as the gases progressively burn, expand, and advance with progressively increasing 50 velocity toward and through the mouth of the port.

When the furnace is reversed and the port P becomes the outgo port, the unconstricted mouth and throat of my port offers minimum resistance to the flow of waste gases from the furnace to the regenerator 3. Within the port there are no shoulders or other protuberances, such as might tend to obstruct the flow of the waste gases and to cause precipitation of the particles of dust and molten material entrained therein, as usual. It will also be observed that the end-wall 8 of the port is recessed at 15, in such manner that the inner face of the burner 4 is offset from the inner face of said wall 8 and lies below the inner end 12a of the floor of the port. Thus, the body of the burner 4, and particularly the fuel-injecting slot 7 of the burner, lies out of the line of flow of the waste gases streaming through the port, whereby it is impossible for dust and slag in- 70 75 78 80 85 90 95 98 99 100

cluded in the waste gases to accumulate upon the burner and plug such slot 7.

Whereas in the foregoing specification the opening through which the fuel enters my port is shown as an elongate slot 7, it is contemplated that a plurality of orifices may be so arranged longitudinally of the burner manifold, i. e. transversely of the end-wall 8 of the port structure, as to inject the fuel substantially in the form of 10 a sheet that merges tangentially with the primary combustion air.

It is to be understood that the principles of my invention may, advantageously, be embodied and employed in open-hearth furnaces, and in 15 other sorts of furnaces in which it is desired to project a column of fuel and air into a furnace chamber. I have spoken of the throat 10 of the port as a horizontally extending throat, and it is to be noted that by such expression I do 20 not limit the invention to a throat or passage which literally is horizontal. On the contrary, I intend a passage whose general extent is in horizontal direction, and include within the 25 terms of the appended claims passages which are inclined to the horizontal, as the usual throats of open-hearth furnace ports are inclined. And it is manifest that the vertical passages 11a and 11b leading into the throat of the port may 30 be inclined to the vertical without departing from the essence of the invention.

In this case the means for preheating combustion-sustaining air entering the port comprise a regenerator including a single body of checkerwork. It will be evident to those skilled in the 35 art that two bodies of checkerwork may be embodied in the regenerator and vertically partitioned from one another to operate in the manner described, or the two bodies of checkerwork may be arranged in companion regenerators. Indeed, the provision of more than two 40 vertical passages is contemplated within the terms of certain of the appended claims. And it is to be understood that such obvious modifications 45 as these do not avoid the spirit of the invention.

I claim as my invention:

1. A furnace port including vertically and horizontally extending walls defining a passageway for air streaming from air-preheating means 50 into a furnace, and fuel injecting means opening through the vertically extending walls of the port and off-set from the line of gaseous flow in said passageway, whereby, when the port is serving as an outgo port for the waste gases of said 55 furnace, said last means are protected from the usual solid and molten inclusions in said waste gases.

2. The method of firing a regenerative furnace, which method consists in leading air from hot 60 checkerwork upward through two passages, one more remote and one less remote from the furnace, directing fluid fuel angularly into the air flowing upward in the less remote passage, and, by contact with the upwardly streaming air, deflecting the flowing fuel into an upward course 65 of flow, directing the air flowing upward in the more remote passage, in the form of an air curtain, horizontally across the open mouth of the less remote passage and transversely of the 70 merged streams of air and fuel flowing upward

therefrom, and thereby bending and folding such merged streams of air and fuel under said horizontal air curtain and into a horizontally extending column, and projecting such column, with the merged air and fuel streams first mentioned 5 lying beneath said air curtain, into said furnace.

3. The method of firing a regenerative furnace, which method consists in leading air from hot checkerwork upward through two passages, one more remote and one less remote from the furnace, 10 directing fluid fuel angularly into the air flowing upward in the less remote passage, and, by contact with the upwardly streaming air, deflecting the flowing fuel into a vertical course of flow, directing the air flowing upward in the more 15 remote passage, in the form of an air curtain, horizontally across the open mouth of the less remote passage and transversely of the merged streams of air and fuel flowing upward therefrom, and thereby bending and folding such 20 merged streams of air and fuel into a horizontally extending column in which the stream of fuel including quantities of primary combustion air lies lowermost, and projecting such column, 25 with the merged air and fuel streams first mentioned lying beneath said air curtain, into said furnace.

4. The method of firing a regenerative furnace, which method consists in leading a fluid fuel and primary combustion air vertically through an 30 upwardly open passage and into the throat of a horizontally extending firing port, preheating secondary combustion air and feeding it under the influences of draft and buoyancy into said 35 port and leading it across the open mouth of said passage and transversely of said stream of primary air and fuel, and thereby bending and folding said ascending streams of primary air and fuel to provide in said port a relatively long column of advancing gases in which a mixed and 40 burning stream of fuel and primary air is screened from above by a curtain of said secondary air, and, as the gases in the column progressively burn, expand and advance through the port and into the furnace with progressively increasing 45 velocity, maintaining the cross-section of said elongate column at substantially uniform value.

5. A furnace port including a vertical passage for leading air upwardly into a horizontally extending passage, a fuel inlet opening through the 50 wall of said vertical passage, the mouth of said inlet being horizontally offset outward from the effective inner face of the wall of said vertical passage, whereby, when said port is serving as the outgo port for the waste gases of the furnace, 55 the mouth of said inlet is shielded from the usual solid and molten particles included with such gases.

6. A furnace port including a vertical passage for leading air upwardly into a horizontally extending passage, a manifold embodied in the wall of said vertical passage, said manifold including a fuel-ejecting opening horizontally offset from the adjacent wall portions of said vertical passage, whereby, when said port is serving as the 65 outgo port for the waste gases of the furnace, the mouth of said opening is shielded from the usual solid and molten particles included with such gases.
